United States Patent Office.

JACOB EUTENEUER, OF PEORIA, ILLINOIS.

Design No. 2,838, dated November 26, 1867.

DESIGN FOR DOOR-KNOBS.

The Schedule referred to in these Letters Patent and making part of the same.

TO ALL WHOM IT MAY CONCERN:

Be it known that I, JACOB EUTENEUER, of Peoria, county of Peoria, State of Illinois, have invented and produced a new Design for Door-Knobs, of which the following is a full, clear, and exact description, reference being had to the drawing annexed, and making a part of my specification, in which—

Figure 1 represents a view of the outer surface of my door-knob.

Figure 2 represents a side view of the same.

My invention consists in forming door-knobs with their outer surface corrugated by eight radial corrugations, which, starting from a common centre, gradually enlarge as they approach and pass the periphery of the knob.

What I claim as my invention, and desire to secure by Letters Patent, is—

The design for door-knobs, as herein shown and described.
